[57] CLAIM

The ornamental design for a hanging file folder, shown and described.

DESCRIPTION

FIG. 1 is a front perspective view of a hanging file folder showing my new design, the rear view being a mirror image thereof;

FIG. 2 is a bottom plan view;

FIG. 3 is a side elevational view, the opposite side being a mirror image thereof; and

FIG. 4 is a top plan view thereof.

FIG. 1.

FIG. 3.

FIG. 2.

FIG. 4.
